UNITED STATES PATENT OFFICE.

GEORGE PANKUCH, OF CLEVELAND, OHIO.

POT-MOUTHPIECE WIPER FOR TYPE-CASTING MACHINES.

Application filed July 24, 1926. Serial No. 124,735.

This invention relates to a pot mouthpiece wiper for type casting machines, and has for its object to provide an automatic device for cleaning the face of the mouthpiece after each casting operation.

In machines of the character above referred to, a pot containing molten metal is intermittently moved to bring its outlet or mouthpiece into engagement with the face 10 of a type mold and the metal is forced under pressure from the pot into the mold. Unless the faces of the mold and pot mouthpiece are maintained in perfect engagement during the passage of metal from the mouthpiece into the mold, there will be a leakage of metal between the opposed faces of the mouthpiece and mold, and if any metal solidifies on the face of the pot mouthpiece the result will be to increase the gap 15 between the mouthpiece and mold upon subsequent engagement thereof, causing increased waste of metal and necessitating the stoppage of the machine at intervals to clean the mouthpiece.

A perfectly accurate fit between the mouthpiece and mold is exceedingly difficult to maintain in the practical operation of the machine, and consequently there is a loss of metal occasioned by leakage and loss of 20 time occasioned by frequent stoppages for cleaning the mouthpiece.

An important object of the present invention is to provide means for keeping the face of the mouthpiece clean so that there 25 will be a minimum loss of metal due to leakage and the loss of time occasioned by the stopping of the machine for the purpose of cleaning the mouthpiece will be eliminated.

A further object is to provide a wiper 30 on the mold carrier which moves past the mouthpiece immediately behind the mold and wipes the face of the mouthpiece immediately after each discharge of metal therefrom, to keep the face of the mouthpiece 35 free from pot metal.

A further object is to provide a wiper on the mold carrier which will not interfere with the operation of the slug trimming knife commonly employed in machines of 40 this character, which sweeps across the face of the mold to trim excess metal from the base of the slug therein.

A further object of the invention is to 45 provide a yieldably mounted wiper which is so supported that it will be held flat against

the face of the pot mouthpiece while it is moving across the same.

With the above and other objects in view, the invention may be said to comprise the device as illustrated in the accompanying drawings hereinafter described and particularly set forth in the appended claims, together with such variations and modifications thereof as will be apparent to one skilled in the art to which the invention app- 60 pertains.

Reference should be had to the accompanying drawings forming a part of this specification, in which Fig. 1 is a vertical section taken immediately to the rear of the 70 mold disk supporting arm and showing the rear face of the disk and wiper attachment in elevation. Fig. 2 is a front elevation of a mold disk with the wiper attachment thereon. Fig. 3 is a top plan view of the 75 mold disk and its supporting arm showing the wiper trip members on the disk support. Fig. 4 is a fragmentary vertical section through the pot mouthpiece and the portion of the disk adjacent thereto showing the 80 wiper in engagement with the mouthpiece. Fig. 5 is a front elevation of the wiper attachment. Fig. 6 is a section taken on the lines indicated at 6—6 in Fig. 5. Fig. 7 is a section taken on the line indicated at 7—7 85 in Fig. 5. Fig. 8 is a perspective view of the wiper setting trip member. Fig. 9 is a sectional perspective view showing the wiper releasing trip member in place on the 90 mold disk supporting arm.

Referring to the accompanying drawings, the present invention is shown applied to the mold disk 1 of a well known type casting machine. This disk is rotatably mounted on a stud 2 which is secured to a supporting arm 3 which is parallel and closely adjacent the rear face of the disk and forms a part of the slide which forms the support for the disk, there being an arm 4 extending rearwardly from one end of the arm 3 95 which is adapted to slide in a fixed guideway in the machine. The mold disk 1 is intermittently rotated during the operation of the machine by means of suitable gearing meshing with the toothed periphery 5 of the 100 disk. The disk 1 is provided with a series of apertures 6 each of which is adapted to receive a mold 7 which is formed to fit in an aperture 6 and is adapted to be secured to the face of the disk by means of a flange 105 110

8 which lies upon the outer face of the disk and is secured to the disk by means of screws 9.

The molten metal is delivered into the mold from a suitable molten metal pot 10, a portion of which is shown in Fig. 4. The pot 10 is provided with an outlet passage 11 and with a flat mouthpiece 12 provided with a row of small openings 13 which are adapted to register with the slot of the mold when the pot is shifted toward the disk to bring the pot mouthpiece into engagement with the mold. In the operation of the machine the disk 1 is stopped with a mold in alignment with the mouthpiece, the mouthpiece is brought into engagement with the mold and the mold filled with molten metal. The pot is then retracted and rotation is imparted to the mold disk. The supporting arm 3 carries a trimmer knife 14 which engages the inner face of the mold as the mold passes the same and trims the base of the slug in the mold. The parts so far described are all old and well known and are described merely for the purpose of making clear the function and operation of the present invention.

The present invention as herein illustrated consists of a wiper attachment which is mounted upon the mold disk and acts to automatically wipe off the face of the pot mouthpiece after each discharge of molten metal therefrom into a mold. The wiper frame 15 is of substantially the same size and shape as a mold, being provided with an attaching flange 16 adapted to be secured to the outer face of the mold disk by means of attaching screws 17 and having a body portion 18 which is adapted to fit in one of the mold receiving openings 6 of the disk. The frame 15 is provided with a longitudinal slot 19 in which is mounted a wiper supporting arm 20 which is pivoted at its end upon a pin 21 extending across the slot at one end thereof. The arm 20 has attached thereto a flat, resilient metal bar 22 which extends beyond the end thereof and is provided adjacent its outer end with spaced, inwardly projecting lugs 22a between which is mounted a channel shaped holder 23 which is connected adjacent its center to the lugs 22a by a transverse pivot 24. The holder 23 forms a support for a wiper block 25 which is preferably composed of asbestos impregnated with graphite. The arm 20 is normally held in a retracted position in which the wiper block 25 lies entirely within the plane of the inner face of the disk by means of a spring 26 which is connected at one end to a pin 27 carried by the arm 20 and the other end to a pin 28 fixed to the supporting frame 15. For shifting the wiper supporting arm 20 outwardly against the action of the spring 26 to bring the wiper into mouthpiece engaging position

there is provided an actuating lever 29 which is pivoted intermediate its ends upon a pivot pin 30 extending across the slot 19 parallel with the pivot pin 21 and intermediate the ends of the slot. The action of the spring 26 is to normally hold the arm 20 and resilient extension 22 flat against the inner side of actuating lever 29. However, if the actuating lever 29 is rocked about its pivot 30 in a direction to move inwardly the end of the lever 29 which is nearest the pivot 21 of the arm 20, the arm 20 and the wiper carried thereby will be forced inwardly against the action of the spring 26. Means is provided for retaining the wiper in its inwardly projecting wiping position, and to accomplish this result a latch 31 is carried by the lever 29 at the end thereof which engages with the arm 20. The latch 31 is connected to the lever 29 by a pivot pin 32 and is pressed toward engaging position by a suitable spring 33. The latch is also provided with a retaining shoulder 34 which engages a fixed lug 35 integral with the frame 15 and projecting into the upper portion of the slot 19. From the shoulder 34 to the outer end thereof the latch 31 has a beveled face 36 which engages with the inner edge of the lug 35 when the wiper is in retracted position and which projects beyond the inner face of the disk when the latch is engaged with the lug 35. The lever 29 projects beyond the free end of the wiper carrying bar 22 and at the end thereof is bent inwardly past the end of the wiper to provide a trip arm 37 which has a beveled end 38. A fixed trip member 39 is secured to the disk supporting frame adjacent the point of connection of the arms 3 and 4 thereof, and this trip member is provided at its upper end with a hook portion 40 which is adapted to be placed over the upper edge of the slide arm 4 which projects beyond the inner side of the arm 3 and at its lower end with a flange 41 which is adapted to extend beneath the lower edge of the disk supporting arm 3. The trip member 39 is rigidly secured in place on the disk support by means of a set screw 42 in the flange 41 which is adapted to be screwed into engagement with the lower edge of the supporting arm 3. The end of the hook portion 40 is provided with a beveled edge 43 which projects inwardly to adjacent the inner face of the mold disk and lies in the path of movement of the beveled end 38 of the trip arm 37 of the actuating lever 29. Secured to the opposite end of the disk supporting arm 3 there is a second trip member 44 which is substantially U-shaped and adapted to fit upon the upper edge of the supporting arm 3. The U-shaped member 44 carries a set screw 45 by which it may be rigidly clamped to the supporting arm 3 and is provided with an extending lug 46 which is positioned adjacent the inner face

of the mold disk and lies in the path of movement of the beveled portion 36 of the latch 31 when the latch has its shoulder 34 in engagement with the lug 35.

5 In the operation of the machine, the mold disk 1 is intermittently rotated in the clockwise direction as viewed in Fig. 1 to bring a mold into alignment with the pot mouthpiece, and after the mold has been filled 10 with metal the disk is again rotated in the same direction to carry the mold past the slug trimming knife 14. The latter movement of the mold disk carries the wiper attachment 15 past the pot mouthpiece and 15 during the movement of the wiper attachment the trip arm 37 is engaged by the beveled portion 43 of the fixed trip member 39 causing the trip arm 37 to be forced inwardly and rocking the lever 29 upon its 20 pivot 30 and the arm 20 upon its pivot 21 until the shoulder 34 of the latch 31 clears the lug 35 and is forced into engagement therewith by the spring 33. This movement causes the wiper block 25 to be moved outwardly into mouthpiece engagement position and to be locked in this position by the latch 31. As the wiper block 25 engages the mouthpiece, it will be pressed toward the mold disk and will be yieldingly pressed 25 against the mouthpiece by the resilient arm 22 and will be held flat against the mouthpiece by reason of the pivotal connection between the block 25 and the arm 22. If any molten metal should have been deposited 30 upon the face of the pot mouthpiece, this metal will be entirely removed by the wiper block 25 in its passage across the mouthpiece, leaving the face of the mouthpiece smooth and clean for its next engagement 35 with the mold. After the wiper block 25 has passed the mouthpiece, the beveled end 36 of the latch 34 will strike the lug 46 of the fixed trip member 44, causing the shoulder 34 to be pushed off the lug 35 and the wiper 40 to be retracted by the spring 26 to the position shown in Fig. 6 of the drawing, the lever 29 being also restored to the position shown in Fig. 6 so that the trip arm 37 will again engage with the fixed trip member 39 45 after a subsequent filling of the mold. The wiper is thus held in extended wiping position while passing between the trip members 39 and 44 and in retracted position entirely within the inner face of the disk during the remainder of the rotation so that the wiper does not in any way interfere with the operation of the trimming knife 14.

Having described my invention, I claim:

1. In a type casting machine, the combination with a molten metal pot having a mouthpiece and a member movable transversely of the mouthpiece and having a plurality of mold supporting portions, one of said mold supporting portions carrying a 55 mold with which said mouthpiece intermit-

tently engages, of a wiper attachment having a frame adapted to be mounted on one of said mold supporting portions and a mouthpiece wiper yieldably mounted on said frame.

2. In a type casting machine, the combination with the molten metal pot having a mouthpiece and the member movable transversely of the mouthpiece and having a plurality of mold supporting portions, one of said portions carrying a mold with which the mouthpiece intermittently engages, of a wiper attachment adapted to be mounted on one of said mold supporting portions and having a wiper movable across the face of the mouthpiece during movement of said member.

3. In a type casting machine, the combination with the molten metal pot having a mouthpiece and the member movable transversely of the mouthpiece and having a plurality of mold supporting portions, one of said portions carrying a mold with which the mouthpiece intermittently engages, of a wiper attachment adapted to be mounted on one of said mold supporting portions and having a wiper movable across the face of the mouthpiece during movement of said member, and means for automatically shifting the wiper into and out of mouthpiece 95 wiping position.

4. In a type casting machine, the combination with the molten metal pot having a mouthpiece and the member movable transversely of the mouthpiece and having a plurality of mold supporting portions, one of said portions carrying a mold with which the mouthpiece intermittently engages, of a wiper attachment adapted to be mounted on one of said mold supporting portions and having a wiper movable outwardly therefrom to a position in which it will engage the face of the mouthpiece during movement of said member, and means controlled by the movement of said member for shifting the wiper to engaging position, holding the same in engaging position while passing the mouthpiece and retracting the wiper after it has passed the mouthpiece.

5. In a type casting machine, the combination with a molten metal pot having a mouthpiece and a rotatable mold disk having its inner face adjacent the mouthpiece and provided with a plurality of apertures, of a mold in one of the apertures, a wiper attachment in another aperture provided with a wiper movable toward and from the mouthpiece, and means for automatically shifting the wiper toward the mouthpiece and for yieldingly holding the same in engagement therewith while the wiper is being carried past the mouthpiece, and means for automatically retracting the wiper after it has passed the mouthpiece.

6. In a type casting machine, a rotatable

- mold disk having a plurality of apertures each adapted to receive a mold and one of said apertures having a mold supported therein, a molten metal pot having a mouthpiece adapted to be brought into engagement with a face of the mold, a wiper movably mounted on the disk and positioned in one of said mold apertures, means for normally holding the wiper inwardly of the plane of the face of the mold with which the mouthpiece engages, means for automatically shifting the wiper outwardly to mouthpiece engaging position and for holding the same in engagement with the mouthpiece while passing the same, and means for automatically retracting the wiper after it has passed the mouthpiece.
7. In a type casting machine, a rotatable mold disk having a mold supported thereon, a molten metal pot having a mouthpiece adapted to be brought into engagement with a face of the mold, a wiper movably mounted on the disk, means for normally holding the wiper inwardly of the plane of the face of the mold with which the mouthpiece engages, means including a fixed trip on one side of the mouthpiece for shifting the wiper to mouthpiece engaging position, means for retaining the wiper in mouthpiece engaging position, and means including a fixed trip on the opposite side of the mouthpiece for releasing the wiper.
8. In a type casting machine, the combination with a rotatable mold disk provided with apertures and having a mold in one aperture, of a wiper movably mounted in one of the apertures of the disk, and means for automatically shifting the wiper to a position beyond the inner face of the disk and for retaining the same in said position during one portion of the revolution of the disk, and means for automatically retracting the wiper and retaining the same in retracted position during another portion of the revolution of the disk.
9. In a machine of the character described, a wiper attachment comprising a supporting member, a pivoted arm carried by said member, a wiper carried by said arm, a movable actuating member engaging said arm, a spring acting on said arm for normally holding the same in retracted position, said member being movable to shift said arm in opposition to said spring, and a latch for retaining the arm in shifted position.
10. In a machine of the character described, a movable member, a wiper attachment carried by said member and comprising an arm pivoted to said member, a spring acting on the arm to normally hold the same in retracted position, an actuating member movable to shift the arm in opposition to the spring, and a retaining latch for holding said arm in shifted position, and fixed trip members engageable with said actuating member and latch.
11. In a type casting machine having a mold carrier provided with apertures to receive molds, a wiper attachment comprising a frame adapted to fit in a mold aperture, a resilient arm carried by said frame, and a wiper block pivoted intermediate its ends to said arm.
12. In a type casting machine, the combination with a rotatable mold disk having a mold supported thereon and an aperture at one side of said mold, and a molten metal pot having a mouthpiece adapted to be brought into engagement with the face of the mold, of a wiper attachment comprising a frame having a portion fitting in said aperture, an attaching portion engaging the outer face of the disk and a mouthpiece wiper mounted on the frame for movement from a position within the aperture to a mouthpiece engaging position inwardly of the inner face of the disk.
13. In a type casting machine, the combination with a rotatable mold disk having a mold supported thereon and an aperture at one side of said mold, and a molten metal pot having a mouthpiece adapted to be brought into engagement with the face of the mold, of a wiper attachment comprising a frame having a portion fitting in said aperture, an attaching portion engaging the outer face of the disk and a mouthpiece wiper mounted on the frame for movement from a position within the aperture to a mouthpiece engaging position inwardly of the inner face of the disk, and trip controlled means for shifting said wiper and for retaining the same in retracted position.
- In testimony whereof, I hereunto affix my signature.
- GEORGE PANKUCH.
